JESSE A. POLLARD, OF OAKLAND, MISSISSIPPI.

SAND AND GRAVEL PUMP.

1,316,507.

Specification of Letters Patent. Patented Sept. 16, 1919.

Application filed April 30, 1919. Serial No. 293,894.

To all whom it may concern:

Be it known that I, JESSE A. POLLARD, a citizen of the United States, and a resident of Oakland, in the county of Yalobusha and 5 State of Mississippi, have invented a new and Improved Sand and Gravel Pump, of which the following is a full, clear, and exact description.

This invention relates to sand and gravel pumping apparatus and has for an object, 10 the provision of an improved construction wherein air is utilized in removing sand and gravel from a well.

Another object of the invention is to provide a pumping apparatus in which sand and gravel may be removed from a bed beneath the surface of the earth in connection with the water contained therein by the use of intermittent blasts of air into the sand 20 and gravel at the proper point.

A further object more specifically, is the provision of means for removing sand and gravel from any desired depth below the surface of the earth through the use of a 25 casing open or perforated at the bottom and air supply and gravel discharging pipes extend to near the bottom of the casing, the arrangement being such that as the gravel enters the casing it is taken up and 30 forced through the gravel pipe to a convenient point on the surface.

In the accompanying drawing:

Figure 1 is a sectional view through a 35 casing and associate parts disclosing an embodiment of the invention.

Fig. 2 is a transverse section through Fig. 1 on line 2—2, the same being on an enlarged scale.

Referring to the accompanying drawings 40 by numerals 1 indicates the surface of the earth and 2 a casing sunk to the desired depth so that the lower end will be embedded in the bed or strata 3 of sand and gravel. Preferably the lower end is embedded in the sand or gravel 3 though this 45 is not always necessary. It is, however, necessary to have some opening at or near the bottom of the casing 2, preferably the bottom of casing 2 being open completely and 50 also the bottom part of the casing provided with a number of apertures 4. Arranged in the casing 2 is a sand and gravel discharge pipe 5 which extends to near the bottom of casing 2 and to a point above the 55 top where it is connected by suitable con-

nections to a discharge pipe 6, said connection being preferably a swivel joint or connection so that pipe 6 may be swung around to different places, so that the pipe 7 of sand and gravel may be distributed easily. A 60 dam or embankment 8 is provided near the casing 2 and surrounds the casing, there being a gate 9 adjacent the casing and connected with certain parts of the embankment so that no water can flow into the 65 casing 2 unless the gate 9 is opened.

During the normal operation of the pump sand and gravel together with a supply of water will be discharged on to pile 7 and the water would naturally form a pond 10, 70 which would ordinarily flow back into the casing 2 except for the gate 9. This arrangement is provided in order that the supply of water may be had whenever desired, as sometimes the natural inflow of 75 water into the bottom part of casing 2 is not sufficient to take care of the pumping operation. Associated with the sand and gravel pipe 5 is an air pipe 11, which is connected to pipe 5 at 12, which is near the bottom of 80 the pipe. A level 13 of water is provided in the casing 2, said level being of sufficient height to provide a proper resistance to the action of the air entering pipe 5, at point 12. The upper end of pipe 11 is connected 85 with pipe 14 which in turn is connected to any suitable source of air supply, which is preferably discharged into the pipe 11 and therefrom in intermittent blasts as indicated by the air bubbles 15. Normally the sand bed 3 is saturated with water so that when the casing 2 and pipe 5 are first forced into the bed said casing and pipe will be partially filled with gravel and sand as well as water, so that as soon as the first blast 90 of air enters the pipe 5 at point 12 a certain quantity of sand, gravel and water will be raised a predetermined distance. If the air is then turned off more sand and gravel will take its place under the action of gravity so that a second blast of air will lift the column a little farther and so on until eventually there is a continuous discharge through pipe 6. In case of a continuous discharge of air the suction created thereby 95 will draw the water and loose sand and gravel into pipe 5 and force the same out through discharge pipe 6. If this action should result in lowering the water level 100 13 too far gate 9 is opened somewhat so as to 105

allow some of the surface water in the pond 10 to flow into the casing and thereby make up for the lack of water in the sand bed.

- During the pumping operation if the sand 5 and gravel should cave in to an undesirable extent the pipe 5 together with pipe 11 could be raised by any suitable derrick connected to the swivel joint at 16. This pump is adapted to pump sand from any loose bed, 10 but is especially adapted to be used in connection with a sand and gravel bed beneath the overflow district of the Mississippi river. This overflow district in times past was covered by the ocean, but is now covered by 15 earth so that the original ocean bed and sandy shores are buried beneath tillable earth. In order to get at the sand in a direct manner the casing is sunk in any desired manner and then the pumping outfit supplied, which 20 will lift the sand and gravel at a maximum speed with a minimum expense. As the wells are never very deep the casing may be pulled up and moved from time to time as desired.
- 25 What I claim is:
1. A sand and gravel pumping outfit comprising a casing adapted to be sunk into the earth until the lower end thereof is projecting into the sand and gravel bed, said 30 lower end being open, a sand pipe open at

the lower end positioned in the casing, means for maintaining a certain water level in said casing, an air pipe extending through the upper part of the casing to near the bottom of said casing, said air 35 pipe being connected with the sand and gravel pipe near the bottom of the sand and gravel pipe, a swinging discharge pipe connected with the upper end of said pipe, means acting as a container for receiving 40 water and sand from said discharge pipe, guiding the water to said casing, and a gate for controlling the water as it passes into said casing from said container.

2. A sand and gravel pumping apparatus 45 comprising a casing adapted to extend into a sand bed, a sand and gravel pipe extending through the casing to near the bottom thereof, said casing and said pipe both being open at the bottom, an air pipe connected 50 to said sand and gravel pipe near the bottom thereof, a discharge pipe connected with the upper edge of said sand and gravel pipe, an embankment surrounding the discharge end of the discharge pipe, and means 55 including a gate for regulating the flow of water into said casing from within said embankment.

JESSE A. POLLARD.
